Primary Examiner — Michelle E. Wilson*Assistant Examiner* — Clese Moore, Jr.(57) **CLAIM**

The ornamental design for a cover for a bicycle chainring, as shown and described.

DESCRIPTION

FIG. 1 is an isometric view of a top, front, and left side view of an ornamental design for a cover for a bicycle chainring; FIG. 2 is a front elevational view of the cover of FIG. 1; FIG. 3 is a rear elevational view of the cover of FIG. 1; FIG. 4 is a right side elevational view of the cover of FIG. 1;

FIG. 5 is a left side elevational view of the cover of FIG. 1; FIG. 6 is a top plan view of the cover of FIG. 1; FIG. 7 is a bottom plan view of the cover of FIG. 1; and, FIG. 8 is a front elevational view of the cover of FIG. 1 attached to a bicycle chainring and crankarm.

The dash-dash-dash lines are included for the purpose of illustrating portions of the cover that form no part of the claimed design. The dash-dot-dash lines are included for the purpose of illustrating boundary lines and form no part of the claimed design.

1 Claim, 5 Drawing Sheets(56)
